CLAIM

The ornamental design for a mass airflow housing interface, as shown and described.

DESCRIPTION

FIG. 1 is a top exploded view of the mass airflow housing interface.

FIG. 2 is a front view of the mass airflow housing interface.

FIG. 3 is a rear view of the mass airflow housing interface.

FIG. 4 is a left side view of the mass airflow housing interface.

FIG. 5 is a right side view of the mass airflow housing interface.

FIG. 6 is a top view of the mass airflow housing interface.

FIG. 7 is a bottom view of the mass airflow housing interface.

FIG. 8 is a left perspective exploded view of the mass airflow housing interface; and,

FIG. 9 is a right perspective exploded view of the mass airflow housing interface.

1 Claim, 9 Drawing Sheets
